HOT WATER HEATER

Harrison D. Sterick, Pittsburgh, Pa.

Application October 29, 1937, Serial No. 171,646

4 Claims. (Cl. 122—245)

This invention relates to new and useful improvements in instantaneous water heating and storage systems, and it is among the objects thereof to provide a system of the above-designated character, which shall be especially adapted for use in automobile trailers, cottages and the like, where compactness and economy of gas and space is a primary consideration.

It is a further object of the invention to provide hot water heating and storage systems of a construction to efficiently and economically heat water by providing maximum area for heat absorption within a minimum space, and which shall substantially eliminate dripping incident to the so-called sweating of the heating pipes and heater housing.

Another object of the invention is the provision of a water heating system comprising an outer and inner housing, in which the inner housing is intimately engaged by a water heating coil in the form of helical convolutions.

Still a further object of the invention is the provision of a water heating system comprising a plurality of helically formed heating coils disposed one within the other with a housing interposed therebetween and having a combustion chamber in the bottom thereof, from which the products of combustion are directed in intimate contact with the convolutions of the inner coils.

These and other objects of the invention will become more apparent from a consideration of the accompanying drawing constituting a part hereof in which like reference characters designate like parts and in which:

Fig. 1 is a vertical cross-sectional view of a heater housing showing the water heating and circulating coils and storage tank in side elevation; and

Fig. 2 is a similar view of a modified form of the heater shown in Fig. 1.

In Fig. 1 of the drawing, the structure therein illustrated comprises a base 1 of cast metal having a radial flange 2 on which is mounted a burner 3, and a flange 4 for supporting an inner shell 5 and a shell 6, the outer shell or housing 7 being supported in a recess 8 formed by the divergent flange or rib 4 of the base 1. The inner shell 5 is provided with legs or a scalloped or fluted base to permit heat from the burner to boil or evaporate any moisture accumulating on the outside of the tapered housing 6 to pass into a sweat band 9 formed around the base of the inner housing 5. The tapered housing 6, in effect, constitutes a fire box or heating chamber, which is designated by the reference numeral 10, in

which is disposed the heater coil 11 that extends from a T-connection 12 leading to the service line 13 upwardly into the combustion chamber 10, thence above the housing 6 to the top of the heating unit. A cover 14 having flange 15 caps the outer housing 7, and perforations 16 are provided at the top of the inner housing 5 to permit circulation of air from between the walls 5 and 7 into the top of inner chamber and from there to stack. The top 14 is provided with a flanged opening 17 to permit exit of the products of combustion.

Disposed in the upper portion of the inner housing is a hot water storage tank 18, having an outlet connection 19 to the heating coil 11, the connection 19 extending into tank 18 a substantial distance and terminating adjacent the bottom of the tank 18. Tank 18 is also provided with a cold water inlet connection 20 having a coil 21 that is coiled or wrapped around the inner housing wall 5 to the lowermost position of the heater coil 11, and is then coiled or wrapped upwardly or doubled upon itself and terminates at a connection 22 leading to a source of cold water supply.

The burner 3 is connected to a gas line 23 having a thermostat 24 connected in the heating coil to render the burner responsive to the temperature variations of the hot water flowing to the service line. A feature of the invention is the provision of a plurality of relatively long fins 25 in the form of a spiral, in which the heater coil 11 is wrapped or brazed as shown in dotted lines at 26, and from which the coil extends upwardly between the inner housing wall 5 and the wall 20 of the water storage tank 18 to the connection 19 leading into the tank.

A baffle plate 25a is disposed beneath the fins 25, the plate functioning to divert the products of combustion from the center against the side-walls of the burner housing 6 to thereby effect intimate contact of the hot gases with the heating coil 11. The tapered housing 6 terminates in an inclined flange 6a which collects the moisture dripping from the storage tank 18 and diverts it away from the inner heating coil into the drip pan 9.

The inner heating coil 11 or the outer coil 21 may be intimately attached to the housings 5 and 6 as by brazing to effect a more efficient exchange or transfer of heat with the water in the coils.

In the construction shown in Fig. 2 of the drawing, the base and housings are substantially as shown in Fig. 1 with the heater coil in the form of a series of spirals around the storage

tank 18. This construction differs also from that of Fig. 1 in that the cold water inlet designated by the numeral 27 is at the bottom of the heater instead of the top, as shown at 22 in Fig. 1, and 5 the cold water supply line extends in one direction only, upwardly around the inner housing wall 5, to the top of the storage tank.

The construction of Fig. 2 provides more capacity than that of Fig. 1 but is in principle the 10 same as that shown in Fig. 1 with the exception of the single instead of double coiling of the cold water supply line.

The operation of the hereinbefore described, 15 instantaneous and storage water heating system is briefly as follows: With the burner 3 supplying the effective heating temperature in the fire box chamber 10, water in the heater coil 11 is heated and rises upwardly into storage tank 18, in which it circulates so that the tank 18 at all times contains hot water. As the water is drawn from the service line 13, it will pass from the storage tank 18 through the outlet connection 19 downwardly through the heater coil, around the storage tank 18, thence into the spiral fin structure 25 and down through the fire box 10 where the temperature of the water is increased before it passes through the service line 13 to use. As the available supply of hot water in tank 18 is diminished, the temperature will drop in the heater 30 coil 11 and thermostat 24 will increase the fuel supply to the burner 3 to make up the difference in the temperature drop, thereby continuing the supply of water at the desired temperature for an indefinite period. However, the storage tank 18 35 is of such capacity as to furnish a normal demand for hot water at all times without requiring increased consumption of fuel by the burner 3. The feature of the thermostat control is provided to take care of unusual conditions when the heating apparatus is subject to overload.

It will be noted that by the disposition of the heating coil within the housing or fire box 10 and the substantial filling of the space at the top of the fire box housing 6, all the heat in the fire box 45 is absorbed by the coil. However, any heat passing through the central opening of the fin 25 will again contact both the wall of the storage tank 18 and the hot water coil 11, which prevents a straight line flue action of the heat and 50 products of combustion to the stack 17. This function may be accomplished by use of a dry housing of the shape of tank 18 where the system is used only as an instantaneous heater. Furthermore, the heat absorbed by the inner housing 55 6 will be conducted to the cold water supply coil 21, which is wrapped around the inner housing 5 so that maximum heat absorption is obtainable by the arrangement of the hot water and cold water coils, as shown and described.

The space between the outer housing 7 and inner housing 5 permits circulation of air to prevent sweating on both the inner and outer housing walls 5 and 7, and any moisture accumulating on the wall 5 will flow downward into the sweat band 9. Likewise any sweating on the housing 6 of the combustion chamber will accumulate in the sweat band 9 from which it evaporates and passes into the stack 17 through the space between inner housing 5 and outer housing 7.

70 It will be evident from the foregoing descrip-

tion of the invention that hot water heating systems made in accordance therewith provide maximum heating capacity within a minimum space and with a minimum cost for fuel. It also prevents dripping caused by so-called sweating and 5 provides an ideal system for use in trailers or the like.

Although one embodiment of the invention has been herein illustrated and described, it will be apparent to those skilled in the art that various 10 modifications may be made in the details of construction without departing from the principles herein set forth.

I claim:

1. In a hot water heating and storage system, a 15 base supporting a burner, an inner housing open at the top forming a combustion chamber supported on said base, an outer housing supported on said base and an intermediate housing supported on said base, a heating coil disposed in the 20 combustion chamber formed by the inner housing, a storage tank suspended in the top of the intermediate housing, the heating coil extending beyond the combustion chamber and passing around the storage tank to a connection leading 25 to said tank in the top thereof, a cold water supply line connected to the top of the storage tank and having its convolutions disposed intermediate the outer housing and inner housing walls out of contact with the heating coil, said water supply 30 coil extending downwardly and upwardly a distance coextensive with the heater coil and connected to a source of water supply at the top of the heating and storage system.

2. In a hot water heating system, a housing forming a combustion chamber, a second housing disposed around said first named housing and an outer housing disposed around the second-named housing, the housing constituting the combustion chamber being of substantially half the length of 40 the other housings, a heating coil extending upwardly in intimate contact with the inner wall of the combustion chamber and above the combustion chamber in intimate contact with the inner wall of the second-named housing, and a 45 coil extending substantially the full length of the outer wall of the second named housing.

3. A water heater as set forth in the next preceding claim having a sweat box disposed between the outer and intermediate housing at substantially the base of said housings.

4. In a hot water heating and storage system, the combination of a heating coil, a storage tank disposed within said coil, said coil being partially wrapped around said storage tank in helically 55 wound superposed layers and connected to an outlet in said tank, a cold water coil leading to a source of water supply connected to the top of the storage tank and having its convolutions disposed outside of the heating coil a distance coextensive with the heating coil, a housing dividing the water supply and heating coil, and a housing disposed around the water supply coil, a heater at the bottom of said coils and a baffle interposed intermediate the top and bottom extremities of the heating coil, said baffle comprising a spiral fin in which the heating coil is disposed between the convolutions of the fin to constitute the upper limits of a combustion chamber.

HARRISON D. STERICK. 70
